UNITED STATES PATENT OFFICE.

FRED A. SCHMITZ, OF YOUNGSTOWN, OHIO, ASSIGNOR TO THE GENERAL FIREPROOF-
ING COMPANY, OF YOUNGSTOWN, OHIO, A CORPORATION OF OHIO.

FIREPROOF-SAFE CONSTRUCTION.

Application filed November 18, 1922. Serial No. 601,734.

To all whom it may concern:

Be it known that I, FRED A. SCHMITZ, citizen of the United States, residing at Youngstown, in the county of Mahoning 5 and State of Ohio, have invented certain new and useful Improvements in Fireproof-Safe Constructions, of which the following is a specification.

This invention relates to an improvement 10 in fire-proof safes of the type used in offices and the like for preserving records, documents and other valuables from loss by fire.

A primary object of the invention is to provide a safe that may be readily fabricated to meet the desired specifications without the necessity of carrying a large stock of safes of different storage and fire resisting capacities.

To that end the invention contemplates 20 a fire-proof safe construction comprising a fabricated metal frame consisting of parts that may be made in quantities and kept in stock and then readily assembled in the proper order to provide a skeleton frame- 25 work on and about which a plastic cementitious fire-proof material may be molded to provide walls of the desired thickness according to the kind of safe desired, that is, according to its heat-resisting requirements.

It is well known that the rise of temperature within the storage compartment of a safe is in inverse ratio to the mass of material constituting the walls, and therefore 35 the thicker the walls the greater the heat resistance. And, in order to readily meet specifications calling for thicker walls the present invention contemplates the use of a plurality of standardized parts which permit of readily assembling, and tightly and neatly interfitting to produce a safe of the desired wall thickness by repeating the use of certain of the molding sections forming 40 the door frame.

Another object is to provide a construction wherein the top, sides and bottom of the interior insulation-unit are integral or cast in one piece, thereby providing in effect an open fireproof shell, the back of 45 which is made by a separate pre-formed panel or section fitting into a properly prepared seat at the rear of the shell, and the joint formed at the seat being sealed by a fire resisting cement while the front of the

open shell is closed by swinging fire-proof 55 doors. In that connection the present invention distinguishes from safes wherein the back is molded integral with the sides, top and bottom of the interior part or unit, and which do not afford the advantages of 60 construction and assembly provided by a safe made in accordance with the present invention.

A further object is to provide a safe, 65 which, when completed is prepared to withstand high temperature and possesses great strength against cracking or breaking open in event that it should be struck by a falling part of a burning building structure, or if the safe itself should fall from a 70 height as a result of a fire.

A still further object of the invention is to provide novel means for retarding the transmission of heat by conductivity from the outside casing of the safe through the 75 door frame to the inner part of the safe, thereby materially augmenting the factor of safety.

With the above and other objects of the invention, which will more readily appear 80 as the nature of the invention is better understood, the same consists in the novel construction, combination, and arrangement of parts, hereinafter more fully described, illustrated and claimed.

A preferred and practical embodiment of 85 the invention is shown in the accompanying drawings, in which:

Figure 1 is a perspective view of a completed safe.

Figure 1^a is a view of the primary structural element used as the basis of construction for the door frame.

Figure 2 is a horizontal sectional view taken on the line 2-2 of Figure 1.

Figure 3 is a vertical cross sectional view taken on the line 3-3 of Figure 1.

Figure 4 is a vertical cross sectional view taken at right angles to Figure 3.

Figure 5 is a perspective view of the fabricated metal frame prior to the fire-proof composition being molded thereon.

Figure 6 is a perspective view showing the fabricated frame having the fire-proof filling molded thereon and the pre-formed 105 back section about to be inserted to the open shell.

Figure 7 is a detail perspective view of

one of the jamb moldings used in the formation of the door frame.

Figure 8 is a detail perspective view, partly in section showing the manner in which the hinges are supported at the sides of the door frame.

Figure 9 is a detail perspective view partly in section illustrating a lower corner of the safe showing the caster mounting.

10 Figure 10 is a horizontal cross sectional view illustrating a class of safe having thicker side walls than the safe illustrated in Figures 1 to 9 inclusive.

15 Figure 11 is a detail perspective view of the lower corner of the door frame of a safe constructed in accordance with the modification shown in Figure 10.

20 Figure 12 is a detail perspective view, partly in section showing the seam construction for permitting the escape of gases generated within the shell of the safe in case of fire.

25 Similar reference characters designate corresponding parts throughout the several figures of the drawings.

As previously indicated, it is one of the important features of the present invention to provide a construction which may be readily fabricated to meet different specifications, thereby obviating the necessity of carrying many different types of safes made up for use.

30 In order to meet the needs of users of safes of various classes and also to effect desirable economies from a manufacturing, as well as a commercial standpoint, it is proposed to provide a construction which will permit of the making of safes of different classes designated by their wall thickness.

40 That is to say, a safe which must have maximum fire resisting qualities, for example, may be designated as a class "A" safe, the walls thereof being of maximum thickness and the storage compartment being correspondingly smaller while safes of another class, class "B" for example, will have thinner walls and consequently less heat resisting properties but a correspondingly larger interior storage capacity. Safes of other 45 classes may also be made but the types referred to will serve to illustrate the range of application of the invention to safes of different types or classes.

50 For the purpose of illustration, Figures 1 to 9 inclusive of the drawings illustrate a safe of the so-called class "B" or safe cabinet type which has relatively thin walls while Figures 10 and 11 illustrate a safe of the class "A" type wherein the walls are of increased thickness and the interior storage compartment correspondingly reduced due to the use of additional interfitting moldings which widen the frame of the door, as will hereinafter more fully appear.

55 In building a safe of the type herein pro-

posed, the door frame A is preferably the first part constructed and assembled, and with this frame as a base from which to work, a skeleton cage B is provided, the same being open or unobstructed at the rear 70 to receive the back section C, and also open at the front to receive the swinging doors D.

The primary structural element E of the door frame A is preferably a rectangular frame of channel formation and includes the 75 top and bottom frame bars 1-1 and the side frame bars 2-2 whose corners are preferably mitered and welded as indicated at 3 thereby to provide in effect an integral rectangular frame member which is extremely 80 rigid and contributes materially to the strength of the front part of the safe and maintains the corner angles of the door frame true to insure proper fitting of the doors when they are closed.

85 The webs or bottom walls of the channel bars 1 and 2 are provided with a plurality of openings or perforations 4 which permit of the cementitious insulating material constituting the insulation unit or shell of the 90 safe, flowing therethrough to fill the front part of the door frame A, as will presently appear, and to also have the effect of providing additional resistance to the conductivity 95 of heat thereby preventing any tendency of the frame to buckle or warp.

As will be observed more particularly from Figures 3 and 9 the top and bottom frame bars 1-1 have secured thereto in any suitable manner, as by riveting or welding, the head and sill forming members 5 and 6, both of which are of duplicate formation and are reversed in their application to the top and bottom members to provide the head and sill of the main door frame A. The said 100 head and sill forming members 5 and 6 are of channel formation and have the long flanges 5^a and 6^a thereof attached to the bars 1-1 while the short flanges 5^b and 6^b thereof are spaced from the perforated web portion of the main frame members as shown in Figure 3 and carry therewith the coupling strips 7 and 7^a to which the stepped and recessed head and sill moldings 8 and 8^a are attached.

110 It will therefore be apparent that the top and bottom edges of the door frame A consists primarily of the duplicate head and sill forming members 5 and 6 which are attached to the channel bars 1-1 and carry therewith the head and sill moldings 8 and 8^a which are duplicates of each other but reversed in their assembly on the head and sill members to provide the opposite ends of the door opening. As will be observed from 115 Figure 3 the bottoms of the recesses of the moldings 8 and 8^a are provided with elongated key openings 9 which permit of the cementitious insulating material flowing into 120 the space provided by the depth of the open-

ings due to the thickness of the metal to thereby break up the continuity of metal in the door frame and consequently provide additional resistance to the conductivity of 5 heat to the storage compartment or interior of the safe.

The side corners of the door frame A are formed by the angular vertically arranged hinge moldings 10 which are shown to advantage in Figures 2 and 8. These moldings are of similar cross section and are secured to and carried by the vertical frame bars 2 of the primary structural element E, the same being assembled in reverse 10 relation to form the opposite edges of the door frame. As will be observed from the figures referred to the outer flat face 11 of each molding has secured thereto by suitable fastenings 12 and spot welds 13, one 15 leaf 14 of the hinges which carry the doors D. To provide for properly spacing the hinge molding with reference to the bars 2 and also afford adequate anchorage for the fastenings 12, a suitable filler strip 15 is 20 arranged between the inner side of the portion 11 of the hinge molding and the outer flanges of the bars. 25

As previously explained the hinge moldings 10 constitute the opposite vertical corners of the door frame, and are each of substantially flaring cross section thereby providing pockets which are in open communication with the rear of the channel bars 2 through the openings 4 while the 30 inside wings are of angular formation and provide a stepped door seat which includes the obliquely disposed face 16, shoulder 17, recess 18 and attaching flange 19; and the outer wing thereof, which includes the hinge attaching face 11, terminates in an inset keeper flange 20, the purpose of which will hereinafter more fully appear.

The attaching flanges 19 of the hinge or corner moldings 10 are adapted to have 45 secured thereto the standardized jamb moldings 21, which are shown assembled on the hinge moldings in Figures 2, 5 and 6, and are illustrated more in detail in Figure 7. From this figure it will be observed that 50 these moldings are formed to provide the flat door receiving faces 22 and 23 having therebetween the recess 24 the bottom wall 25 therebetween being provided with elongated perforations 26 to receive the 55 cementitious insulating material in the same manner as the openings 9 of the head and sill moldings 8 and 8^a. The flat face 22 is formed with the flange 22^a for attachment to the flange 19 of the hinge molding and 60 the face 23 is provided with the rearwardly extending hook-like keeper flange 27 having a keeper slot 28. This keeper slot may receive an edge of the interior lining as shown in Figure 2, and herein- 65 after referred to more in detail, or it may

receive the flange 22 of a similar jamb molding 21^a as illustrated in Figure 11, and also hereinafter referred to more in detail.

When the top, bottom and sides of the door frame A are thus formed by the head 70 and sill members 5 and 6, the head and sill moldings 8 and 8^a; the hinge or corner moldings 10; the jamb moldings 21, the meeting edges thereof are welded to seal the joints and also maintain a true angular 75 frame.

It will be apparent from the foregoing description that the door frame A may be readily constructed from standardized parts in a simple and expeditious manner, and 80 when the frame is assembled in the manner described there is provided a continuous rectangular pocket for receiving the cementitious insulating material. Therefore, the door frame constitutes a mold for 85 the front part of the safe when the sides, top and bottom are poured and remains an integral part thereof, thus materially contributing to the stability and strength of the structure and insuring accurate seating 90 of the doors.

The skeleton cage B, which constitutes the frame work for the open shell or round-about body of insulating material consisting of the sides, top and bottom, preferably 95 includes in its organization the base channel members 29 the front ends 30 of which are adapted to be secured to the bottom flange 6^a of the sill member 6 and also to the channel bar 1 while the rear ends 31 thereof provide a portion of the seat for receiving the slab constituting the back panel or section C as will presently appear. Also, the frame includes the reinforced slat-like truss members 32 and the upper corner angles 32^a 100 whose front ends 33 are adapted to be welded or otherwise secured to the outer flanges of the side members 2 of the primary structural element E. The upper truss member 32 and corner angles 32^a 105 arranged at the top of the frame are secured to the upper flange 5^a of the head member 5 at their front ends as will be seen from Figures 3, 5 and 6 of the drawings, and thus in that respect are like the 110 front ends 30 of the base channels 29 which engage with the flange 6^a of the sill member 6. The rear ends 34 of the truss members and upper corner angles are preferably 115 inset as shown, and at a suitable distance back from the offset portion have secured thereto the angle members 35 which provide a solid abutment flange 36 against which the back section rests when it is placed in position.

The reinforcing cage on which the cementitious body is built therefore comprises the base channels 29; the horizontally disposed truss members 32; upper corner angles 32^a and the roundabout abutment 120 125 130

angles 35 which provide a substantially continuous metallic abutment for the slab constituting the back section C when the latter is placed in position.

- 5 When the open metallic skeleton of the safe constituted by the door frame A and the cage B are completely assembled the operation of pouring and molding the interior insulation unit or shell is performed with 10 the assistance of suitable removable molds. Thus, the cementitious insulating material constituting the sides F—F, top G and bottom G' of the safe is then poured so that the cementitious material provides a continuous 15 roundabout shell open at the back and front to receive the doors within the portion defined by the door frame and to also receive the back slab C. In the molding of the sides, top, and bottom walls the cementitious material fills and surrounds the parts 20 constituting the door frame A thereby completely embedding the primary structural element E in the insulating material because of the openings or spillways therein, 25 and also filling the key openings in the head, sill, and jamb forming moldings 8—8^a and 21 respectively to provide resistance to the conduction of heat.

When the sides F—F and the top and bottom G—G' are poured and molded, the rear edge thereof is formed with a continuous stepped and mortised seat H whose outer face includes the flanges 36 of the angles 35, thereby providing a continuous channel at 30 the back edge of the molded structure for receiving the complementary tongue and groove tenon portion H', of the slab which constitutes the back panel C; and, which, as previously explained, is pre-cast or 35 formed independently of the body of the safe and subsequently placed in position on the body so that the stepped portion H' thereof will match with the seat H. To insure the adhesion of the back section to the 40 body a suitable fire resisting cement is placed in the seat H thereby also sealing the joint formed between the back slab and the body.

The back section C may obviously be formed in various different ways but preferably includes a rectangular main channel member 37; the opposite vertical members of which are connected by the cross truss members 38 as shown in Figures 2, 3 and 4.

As shown in Figure 6 of the drawings, 55 the rear ends 31 of the base channels 29 and likewise the rear inset ends 34 of the straps or truss members 32 and corner angles 32^a project beyond the roundabout angles 35, thereby to permit the back section to telescope within the same as it is fitted to its seat H on the body. The sides of the channel member 37 are exposed in the finished slab, thereby producing a metal to metal contact 60 between the frame of the back panel and the projecting ends of the cage members and

facilitating the fastening or locking of the back in place on the body by means of screws, other suitable fastenings, or by welding.

The doors D are preferably constructed of 70 metal sheets and standardized moldings which are assembled and filled with the cementitious insulating material, which is allowed to set previous to the hanging of the doors on the hinge moldings 10. As will be 75 observed from Figure 2 the doors D preferably consist of the front sheets 40 which are provided with the inturned shoulder portion 41 at one edge and with the inturned flange 42 at the opposite edge. The inside 80 portion of the sheets 40 adjacent the hinge edges thereof are preferably reinforced, as shown at 43, and the hinge leaves 14^a are secured in position, as shown in Figures 1 and 2, to register with the hinge leaves 14 on 85 the moldings 10. The stepped jamb-mating portion of each door is provided with a keeper flange 44 adapted to receive a similar portion of an inner edge molding 44^a which constitutes the portion of the door which 90 registers and matches with the jamb molding 21 at the sides of the door frame A. The recessed portions of the inner edge moldings 44^a which receive the shouldered portions or ribs of the jamb moldings 21 are 95 provided with elongated openings 44^b for permitting the cementitious material to project through the thickness of the metal and thereby provide additional resistance to heat 100 which would be conducted by the middle of the door toward the interior or storage compartment of the safe. The said inner edge moldings 44^a are preferably fitted with angles 45 adapted to engage with the rear sheets 46 of the doors to provide the interior 105 face thereof, and the said sheets 46 are provided with the inturned flanges 47 for receiving complementary flanges 48 of the angle members 49 which form a part of the joint edge of the door. The angles 49 in turn are 110 connected with the edge portions of the stepped moldings 50 which moldings are standardized stock and, upon being reversed, can be made to fit into each other when used on a right or left hand door. In other 115 words, the moldings 50 are of stepped formation and are adapted to nest one within the other to provide a tight joint at the meeting edges of the door and the alternate valleys resulting from the stepped formation 120 of these moldings are provided with elongated slots for receiving the cementitious material to further insure adequate heat resistance at the meeting edges of the doors. The top and bottom edges of the doors D 125 are formed by suitable moldings 50^a which are counterparts of the head molding 8 and sill molding 8^a, thus completing the doors.

After the vertical sides F—F and top and bottom G—G' are completed, the inte- 130

rior insulating shell is fitted with an interior metallic lining which is assembled and fitted into the cavity formed by the united body and back, and the exterior is covered by a sheet metal casing.

Referring first to the interior lining, which is assembled and then fitted into the body, it will be observed from Figure 2 that the lining sheet 51 covers the inner 10 face of the back panel C and is provided at its opposite side edges with the relatively wide channel 52, while its top and bottom edges are formed with the keeper flanges 53 that provide keeper grooves for receiving the top and bottom liner plates 54 and 55 whose front edges are respectively connected by suitable fastenings to the head molding 8, as indicated at 56, and to the sill molding 8^a as indicated at 57. The 20 wide channels 52 are adapted to receive the angular ends 58 of the side sheets 59 whose front edges are provided with the reversely disposed angle flanges 60 which fit into the keeper grooves 28 of the jamb moldings. 25 As will be observed from Figure 4, the top and bottom edges of the side sheets 59 are provided with the keeper flanges 59^a for interfitting with corresponding side flanges 54^a of the top sheet 54 and flanges 55^a of 30 the bottom sheet 55.

The outside shell or casing is built up or assembled about the cementitious body and preferably consists of the outer side sheets 61 having at their front edges the inturned flanges 62 for fitting into the keeper channels 20 of the hinge moldings 10, while the rear edges thereof are provided with the inwardly and thence outwardly projecting flange portion 63 which provides the outwardly facing keeper grooves adapted to receive the inturned flanges 64 of the back sheet 65 which is slid into position to thereby hold the rear edges of the side sheets securely in place. (See Figure 2.) The 45 top and bottom edges of the side sheets 61 are provided with the inturned flange portions 61^a and 61^b which are respectively fastened to the upper corner angles 32^a and the base channel members 29.

50 The cover 66 for the top wall G is preferably provided at its side edges with the overhanging bead-forming flanges 67, as will be observed from Figure 4, while the back edge thereof is provided with a depending apron flange 68 which flushly fits against the rear outside sheet 65 and seals and protects the upper end of the back when placed in position. The front edge of the cover is provided with an overhanging 55 bead-forming flange 69 which terminates in an inturned attaching flange 70 that is suitably fastened to the coupling strip 7, as shown in Figure 3.

The bottom casing member 71 is a duplicate of the cover 66, and as will be ob-

served from Figures 1 and 3, the front bead or apron 72 thereof is attached to the coupling strip 7^a forming a part of the sill structure of the doorway, while the side flanges 73 engage with the lower edges 70 of the outer side sheets 61, as shown in Figure 4, and the back flange 74 thereof is suitably fastened to the lower edge of the back sheet 65, the fastenings preferably engaging with the channel 37 as well as the back 75 sheet 65 to insure firm anchorage of the facing sheets to the assembled structure. The same comment is true of the fastenings which connect the flange 68 of the top section 66 with the upper edge of the back 80 sheet 65.

Another novel and distinctive feature of the invention is to provide a vented joint or seam construction for the interfitting parts of the outer shell which will 85 permit of the escape of gases generated within the shell or casing in event the safe is subjected to heat, thereby obviating the possibility of buckling or damage due to confining the gases generated by heat of 90 fire. This type of joint may be provided wherever the back or side sections are united by a folded seam as for example at the rear corners of the outside shell, one of which is shown in Figure 12 of the drawings, and wherein it will be seen that the flange 63 is cut away, as indicated at 63^a, to provide a vent or passage to permit the escape of gases at the point x directly between the flange 64 and the main wall of 100 the flange 63.

Figure 9 of the drawings illustrates the manner of attaching the caster or roller devices R for supporting the safe in a portable manner. These caster units are preferably arranged so that they may be fastened to the bottom channel members 29, thereby having a firm and solid anchorage and support for the swiveled rollers or casters which enable the safe to be easily 110 transported or moved about.

Figures 10 and 11 show a safe constructed in accordance with the invention wherein additional moldings are used to widen the door frame and thereby increase the thickness of the walls of the safe. In all essential particulars the construction shown in Figures 10 and 11 is the same as the construction shown in Figures 1 to 9, but it will be noted that the jamb molding 21^a is duplicated in conjunction with the molding 21, thereby to provide additional ribs and grooves at the sides of the doorway and to also increase the thickness of the side walls F'. As shown in Figure 10 the back panel 125 C' is also of increased thickness and likewise the doors D' are thicker than the doors D. The top and bottom walls of the safe are also made thicker, as illustrated at G' in Figure 11, by utilizing wider moldings S, 130

the same having the grooves or valleys thereof provided with openings s' for permitting the plastic cementitious material to break up the continuity of the metal and thereby reduce its conductivity to heat.

It will, of course, be understood that the doors D of the safe may be provided with the knobs or operating handles K , and the usual type of locking means L may also be employed.

From the foregoing it will be apparent that one of the primary distinctive features of the present invention is the formation of a hollow body open at both sides and provided at one side with a door frame for receiving swinging hinged doors and provided at the opposite side with a seat for the back panel or slab which is fitted thereto and sealed in place. It will of course be understood that the back slab does not depend upon the sealing material for uniting and holding the back section to the body of the safe, because the skeleton metallic frame or cage, about which the main body is built, provides for also telescopically receiving the metallic frame of the back panel thereby to permit the frame or cage and the back to be rigidly united or secured together.

Also a further distinctive feature of the invention resides in the structural features and characteristics of the door frame A which constitutes a part of the mold for the front edges of the side walls of the safe.

As shown in Figures 2, 3, 4 and 10 of the drawings, suitable metallic reinforcement such as expanded metal x may be embedded in the sides, top, bottom and back of the fireproof composition while the same is being molded to give added strength and reinforcement to the fireproof body. Furthermore, the valleys of the door joint may be filled with strip asbestos y to prevent heat from penetrating through the joint.

Without further description it is thought that the features and advantages of the invention will be readily apparent to those skilled in the art and it will, of course, be understood that changes in the form, proportion and minor details of construction may be resorted to without departing from the spirit of the invention or scope of the appended claims.

I claim:—

1. A fire-proof safe construction including a monolithic cementitious body unit provided with a front door-opening and with a rear opening surrounded by a joint forming seat, and a separate back panel consisting of a monolithic cementitious unit provided at its inside edge portions with a joint forming seat permanently cemented to said joint forming seat of the body unit.

2. A fire-proof safe construction including a monolithic cementitious body unit having metallic members therein and pro-

vided with front and rear openings and a separate monolithic cementitious back panel arranged to cover and seal the back opening of the body unit and having embedded metallic members joined to the metallic members of the body unit.

3. A fire-proof safe construction including a continuous metal door frame, a monolithic cementitious body unit cast on to said door frame and provided with a front door opening and with a rear opening surrounded by a joint forming seat and a separate pre-cast back panel consisting of a monolithic cementitious unit having its edge portion permanently cemented to the joint forming seat of the body unit.

4. A fire proof safe construction including a metal facing constituting the door frame and of a width corresponding to the wall thickness of the safe, reinforcing elements connected with and projecting rearwardly from the door frame, and a wall forming insulation unit molded about the said reinforcing elements and in and against the door frame.

5. A fire-proof safe construction including a metal door frame, bar-like wall reinforcing elements arranged in spaced relation to form a cage connected with the door frame, and an interior insulation unit molded about the cage and in and against the door frame.

6. A fire-proof safe construction including a sheet metal door frame having openings for receiving and exposing insulation at the face of the door frame, and an interior insulation unit molded in and on to the door frame whereby the insulation fills said openings to retard conduction of heat.

7. A fire-proof safe construction including a stepped door frame having insulation receiving and exposing openings arranged in the valleys thereof, and an interior insulation unit molded in and on to the door frame whereby the insulation will key into said openings and retard the conduction of heat.

8. A fire-proof safe construction including a metallic door frame comprising a primary structural element, door frame forming moldings carried thereby, and a skeleton cage united to said primary structural element and consisting of a plurality of truss members, and an interior insulation unit molded about said cage and against the said door frame.

9. A fire-proof safe construction including a door frame comprising an interior rectangular primary structural element having openings, door frame forming moldings secured to the said primary reinforcing elements and projecting beyond the same to provide a pocket between the structural element and the front of the safe, a reinforce-

ing cage united with the primary structural element and an interior insulation unit molded about the said reinforcing cage and against the door frame and extending through the openings in the primary structural element to fill the pocket between the same and the door frame.

10. A fire-proof safe construction including a metallic door frame comprising a primary structural element of rectangular formation and channel cross section, the web of the channel being provided with openings, door frame forming moldings secured to the said primary reinforcing element and projecting beyond the same to provide a pocket between the structural element and the front of the safe, a reinforcing cage united with the primary structural element and an interior insulation unit molded about the said reinforcing cage and against the door frame and extending through the openings in the primary structural element to fill the pocket between the same and the door frame.

25 11. A fire-proof safe construction including a jacketed metal casing having a frame structure provided with a hollow molding, and a member having openings providing communication between the jacket space of the casing and the space inside of the hollow molding, and a plastic material molded into the space of the jacket and through said openings into the space within said molding.

35 12. A fire-proof safe construction including a jacketed metal casing having a frame structure provided with hollow moldings surrounding the same, and a member having spillways providing communication between the jacketed space of the casing and the space inside of the hollow moldings, and a plastic material molded into the space of the jacket and through said spillways into the space within said molding.

45 13. A fire-proof safe construction including a door frame, reinforcing elements connected with the door frame, an interior insulation shell molded to the door frame and said reinforcing elements, a separate back member consisting of an insulation panel forming the back closure for the shell, and a metal frame embedded in the back member and connected with the reinforcing elements.

55 14. A fire-proof safe construction including a metallic door frame comprising a primary structural element, door frame forming moldings secured to said primary structural element, a reinforcing cage also united to said primary structural element including bottom channel members, upper corner angles and intermediate slat-like truss members, abutment angle strips secured crosswise to the truss members, corner angles and base channels and spaced from the rear

ends thereof, an interior insulation unit molded about said cage and forming the top, bottom and sides of the interior shell of the safe, said interior shell having a seat at the back edge thereof, a back panel 70 adapted to fit in said seat, and means for attaching the back panel to the ends of the members of the cage projecting beyond the said angle strips.

15. A fire-proof safe construction including a metallic door frame comprising a primary structural element and molding sections carried thereby, a skeleton cage connected with the primary structural element of the door frame, abutment elements 75 carried by the skeleton cage and an interior insulation unit molded about said cage and formed with a seat including said abutment elements, a back panel adapted to fit in said seat on the insulation unit, and 80 means for connecting the portion of the cage projecting beyond the abutment elements to the back unit.

16. A fire-proof safe construction including a door frame, a skeleton cage connected 85 with the door frame, an interior insulation shell molded to the cage and door frame, and a separate back member including a metallic frame adapted to be welded to the cage.

17. A fire-proof safe construction including a door frame, a reinforcing cage connected with the door frame, an interior insulation shell molded to the frame and said cage, a separate back member for the shell 90 and for the cage, and outside casing plates 95 for the shell and back.

18. A fire-proof safe construction including a door frame, a reinforcing cage connected with the door frame, an interior insulation shell molded to the frame and cage, a separate back member for the shell and cage, outer side-casing plates interlocking 100 at their front edges with the door frame and having out-turned grooves at their back edges, a rear casing plate interlocking with and holding the side-casing plates at their rear edges, and cover and base casing plates for the top and bottom of the safe.

19. A fire-proof safe construction including a door frame, a reinforcing cage connected with the door frame, an interior insulation shell molded to the frame and cage, a separate back member for the shell and the cage, and an interior box-like lining 115 fitted into the hollow interior insulation shell and secured to the door frame.

20. A fire-proof safe construction including a door frame, a reinforcing cage connected with the door frame, an interior insulation shell molded to the frame and cage, a separate back member for the shell and the cage, outer side-casing plates, and an interior box-like lining adapted to fit within 120 the interior insulation shell, and means for 125

130

- attaching the front edge of said lining to the inner edge of the door frame.
21. A fire-proof safe construction including a metal door frame, a skeleton cage connected at its front end to the door frame, an interior insulation unit molded on to said cage and in and on to the door frame, said insulation unit being formed at its rear side with a seat, a back panel adapted to fit in said seat, and means for connecting the panel to the said seat and cage. 70
22. A fire-proof safe construction including an outer casing, an inner casing, an insulation unit between the two casings, and a door frame consisting of head and sill moldings, side hinge moldings, and jamb moldings interposed between the hinge molding and the inner casing and consisting of standardized parts separably interlocked to vary the width of said jamb molding to determine the wall thickness. 75
23. A fire-proof safe construction including an outer casing, an inner casing, an insulation unit between the two casings, and a door frame consisting of head and sill moldings, hinge moldings, and jamb moldings interposed between the hinge molding and the inner casing, said moldings being standardized parts separably interlocking to vary 80 the width of said inner molding to determine the wall thickness of the insulation unit, and said parts of the door frame being welded together at the corners to form a square frame.
24. A fire-proof safe construction including an outer casing, an inner casing, an insulation unit between the two casings, and a door frame consisting of grooved head and sill moldings, hollow hinge moldings, and 85 grooved jamb moldings interposed between the hollow hinge moldings and the inner casing, said jamb moldings being standardized parts. 90
25. A fire-proof safe construction including an outer casing, an inner casing, an interior insulation unit between the two casings, and a door frame consisting of grooved and slotted head and sill moldings, side hinge moldings interposed between the hinge 95 moldings and the inner casing, said jamb moldings consisting of standardized parts separably interlocking to vary the width of the door frame to determine the wall thickness of the interior insulation unit. 100
26. A fire-proof safe construction including an interior cementitious body and an outside casing for said body including plates having interlocking joints provided with vents. 110
27. A fire-proof safe construction including an outer casing comprising a metallic door frame having locking grooves at its outer side edges, outer side-casing plates interlocking with said grooves, the rear 115 edges of said outer side-casing plates being provided with flanges forming out-turned grooves, said flanges being cut away to provide vent passages, and a back casing plate having means at its side edges for interlocking with the flanges of the outer side plates. 120
28. A door for fire-proof safes consisting of inner and outer casing plates and grooved and slotted door frame forming side-forming moldings, and a cementitious insulating material filling the space between the said casing plates and the side-forming moldings and also keying in the slotted portions of the moldings. 125
29. A fire-proof safe construction including a hollow interior insulation shell open at both sides thereof, a metallic door frame arranged at one of the open sides thereof and a back panel receiving seat formed at the other open side thereof, a back panel adapted to fit into said seat, and plastic means for permanently sealing and bonding the back to the shell. 130
30. A fire-proof safe construction including a hollow interior insulation shell open at opposite sides, a metallic door frame arranged at one side of the shell and the opposite side thereof having a mortised seat and a back panel having a tenon portion for fitting into said mortised seat, means for sealing the joint between the back and the body, and reinforcing means connecting the door frame and the back section. 135
31. A fire-proof safe construction including a skeleton cage open at the front and the back, door frame forming moldings carried by the front of the cage, a fire-proof cementitious composition molded about said frame and flowed into the said door frame and forming an interior shell, and the rear edge of said cementitious shell being formed with a mortised seat, side members of the cage projecting beyond the seat, a back panel having metallic reinforcement therein and provided with a tenon part for fitting into said mortised seat of the body, and means for fastening the projecting ends of the frame members to the metallic reinforcement of the back-panel. 140
32. A fire-proof safe construction including outer or inner casing members, and extensible moldings adapted to be located between the inner and outer casing at the front of the safe to vary the distance between the casing members according to the wall thickness desired, and insulation between the said casing members. 145
33. A fire proof safe construction including a skeleton reinforcing cage for the top, bottom and sides of the safe consisting of a plurality of spaced structural steel members arranged and distributed to provide a trussed reinforcing framework, and an insulation unit molded on and about said cage. 150
34. A fire proof safe construction including a skeleton cage consisting of vertical 155

and horizontal structural steel reinforcing elements, and a continuous metallic door frame rigidly united with said cage, and a hollow insulation unit formed on and about 5 said cage and in and about said door frame.

35. A fire proof safe construction including a fabricated structural steel framework forming top, bottom and side reinforcement, a continuous metallic door frame connected with the front side of said framework, an insulation unit of cementitious material molded in and about the said door frame and on to said framework and formed with a seat at its rear edge, and a back panel 10 also of cementitious insulating material and having therein a reinforcing frame, means for connecting the frame of the back panel with said framework and means for sealing the joint between the back panel and the 15 seat of the insulating unit.

36. A fire-proof safe construction including an insulated safe body having bar-like metallic reinforcing members embedded therein and projecting from an edge thereof, 20 a separate back panel, and means for connecting the back panel with the projecting ends of said bar-like reinforcing members.

37. A fire-proof safe construction including an insulated safe body having a depressed seat and bar-like metallic reinforcing members embedded therein and projecting beyond said seat, a separate back panel including a metallic reinforcing frame, said metallic reinforcing frame of the back panel 35 being adapted to be welded to the projecting reinforcing members of the body.

38. A fire proof safe construction including an insulated safe body, a metallic door frame, side wall casing sheets interlocked 40 with the sides of said metallic door frame, a back casing sheet interlocking with said side casing sheets, and cover and base end plates

for fitting over the ends of the side, back, and casing sheets and also the door frame.

39. A fire-proof safe construction including a cementitious body and a metal door frame provided in the joint faces thereof with a plurality of openings receiving plugs of the cementitious body and also reducing the cross sectional area of the surrounding metal thereby to minimize heat conduction 45 at the door joint.

40. A fire-proof safe construction including a metallic door frame having a plurality of series of openings in the joint faces 50 thereof, the openings of one series being arranged out of registry with the openings of the other, thereby to reduce the cross sectional area of the metal and consequently reduce the heat conductivity of the metal at 55 the door joint.

41. A fire-proof safe construction including a metallic door frame having a plurality of series of openings in the joint faces 60 thereof, the openings of one series being arranged out of registry with the openings of the other, thereby to reduce the cross sectional area of the metal and consequently reduce the heat conductivity thereof, and insulating material filling said openings to 65 the depth of the metal.

42. A fire-proof safe construction including a cementitious body and a sheet metal outside casing for said body consisting of a plurality of plates formed with interlocking 70 flanges arranged to provide a gas outlet for the space confined by said plates.

In testimony whereof I hereunto affix my signature in the presence of two witnesses.

FRED A. SCHMITZ.
